UNITED STATES PATENT OFFICE.

JAMES C. ROSS, OF SEATTLE, WASHINGTON.

FAUCET.

Application filed October 5, 1925. Serial No. 60,433.

This invention relates to faucets and is in the nature of an improvement on the faucet illustrated and described in U. S. Patent No. 1,564,589, issued to me December 1, 1925.

5 The object of my improvements, generally stated, is the perfecting of the faucet disclosed in the patent above referred to for the purpose of lessening cost of manufacture, rendering the valve and parts associated therewith more readily accessible for renewal and repair, and to afford a conveniently controlled self-closing faucet which is peculiarly efficient in operation.

10

15 The invention is illustrated in the accompanying drawing, showing in longitudinal vertical section a faucet embodying my improvements.

According to the present invention the faucet is formed with a substantially cylindrical hollow body 1 having at its lower end, an inlet openings 2, located axially of the body, and communicating through said inlet with a tubular element 3 which is adapted to be secured to a liquid supply pipe, not

20

25 shown.

Above its inlet 2, the body is provided in its peripheral wall with an outlet 4 opening into a spout element 5. The elements 3 and 5 above referred to and the body 1 are, by preference, cast in a single piece. Said body is formed interiorly with two vertically spaced apart chambers 6 and 7, preferably circular in horizontal sections, separated by an apertured partition 8 which is located

30

35 below the level of the bottom of the outlet 4 into said discharge spout.

Above said outlet the inner periphery of the chamber is screw threaded as at 9.

40 Mounted upon the open upper end of the faucet body 1 is a cap member 10 having an upwardly extending portion 11 which is externally screw threaded, and a downwardly extending portion 12 provided with screw threads engaging the internal threads 9 of the body to separably couple the cap thereto.

45 Formed integral with said cap and depending from its extension 12 is a cylindrical cage, indicated generally by 13, having at its lower end a circular flange to make a non-leakable joint at 14 with the partition 8. Extending from said cage through the aperture of said partition into the chamber 7 is a cylinder 15 having an open lower end 16 terminating a short distance above the chamber floor 17 having therein the inlet passage 2.

From its lower end the cylinder 15 is bored, as at 18, upwardly to a peripheral shoulder 19, which shoulder serves as the seat for the faucet valve 20. The external diameter of the cylinder is less than the diameter of the chamber 7 thereby affording an annular channel 21 which communicates with the cylinder bore 18 through peripheral ports 34 provided in the cylinder below the elevation of the valve seat 19. The cap, cage 65 and cylinder, it is to be noted, constitute in its entirety a core which is removable as a single piece from the body.

The valve 20 consists of a piston fitted for axial movement in the cylinder bore 18 to serve as a closure for said ports, said valve is, furthermore, provided at its upper end with a surface 22 adapted to make a tight closure with the seat 19.

Said valve is provided with stem 23 extending axially through the cage 13 into a hole 24 provided in the cylindrical lower end of an operating member 26, the operating member having a stem 27 to which is secured a handle 28 as by means of a headed screw 29. Said operating member is provided with external screw threads 30 engaging screw threads, as 31, provided interiorly of the cap; such interengaging threads being of a pitch sufficient to enable service pressure 85 of water, or other liquid, acting upwardly against the valve to effect endwise movement of the operating member 26 permitting the valve 20 to close against its seat.

The endwise movement above referred to 90 which occurs to the operating member during the closing travel of the valve turns the operating member in one rotary direction, hence by employing the handle 28 to turn said member in the opposite rotary direction 95 the valve is compelled to open with respect to its seat 14 and the ports 34. As hereinbefore explained the piston valve is fitted within the cylinder bore 18 and the valve stem 23 extends into the hole 31 of the operating member 26 and, in consequence, the valve is guided axially of the body by both the core and the operating member which is movable with the valve in both its opening and closing movements. 33 represents 100 a gland-nut taking on the screw threads of the core portion 11, said nut serving as a housing for packing (not shown) provided above a washer 32 which is seated upon the top of the cap, said washer serving as a re-

105

110

movable partition to prevent the packing following the operating member when the latter is actuated to unseat the valve.

The operation of the invention is as follows: The valve 20 is held normally against its seat by means of liquid pressure acting from below against the valve. When the handle 28 is revolved to suitably rotate the operating member, the valve is removed from its seat and also caused to uncover the ports 34 thereby permitting the liquid to travel from the chamber 7 through the annular channel 21 and through the ports into the cylinder bore above the valve, whence it escapes through the cage 13 to the discharge spout 5.

What I claim, is,—

1. A faucet comprising, in combination, a body member having an inlet opening in the bottom thereof and an outlet in its side, said body being provided interiorly with an apertured partition, an interiorly screw threaded core member extending into the body and through said partition, said core being provided with a cage element above said partition and a cylinder provided with ports in its circumferential wall below said partition, said cylinder having a valve seating surface in the upper portion of its bore, a piston-valve within said cylinder, and manually operable means for effecting the opening movement of the valve, said means being provided with external screw threads engaging in the screw threads of the core, said screw threads being of a pitch sufficiently long to enable a pressure of liquid acting axially against the valve to effect the retraction of said means to permit the closing of the valve against its seat.
2. A faucet comprising, in combination, a body member, said body member being provided with an apertured partition dividing

the interior of the body into two chambers, a core member extending into the body member and through the aperture of the partition, said core member being formed below the partition with a bored cylinder element open at its lower end, said cylinder being of a diameter to provide an annular channel between the same and the peripheral wall of the surrounding chamber, ports provided in the peripheral wall of the cylinder and communicating with said channel, a piston provided in the cylinder bore and serving as a valve with respect to said ports, a stem for said piston, an operating member having screw threaded connection with said core, said operating member having a hole therein to receive said stem and cooperating with the cylinder bore to guide the piston.

3. A faucet comprising, in combination, a body member, said body member being provided with an apertured partition dividing the interior of the body into two chambers, a core member extending into the body member and through the aperture of the partition, said core member being formed below the partition with a bored cylinder element open at its lower end, said cylinder being of a diameter to provide an annular channel between the same and the wall of the surrounding chamber, ports provided in the peripheral wall of the cylinder and communicating with said channel, a piston provided in the cylinder bore and serving as a valve with respect to said ports, a stem for said piston, an operating member extending into said core, said operating member having a hole therein to receive said stem and cooperating with the cylinder bore to guide the piston.

Signed at Seattle, Washington, this 17th day of September, 1925.

JAMES C. ROSS.
